DESIGN FOR A LAWN MOWER HANDLE CROSS PIECE

Truman B. Funk, Jackson, Mich., assignor to
Yard-Man, Inc., Jackson, Mich., a corporation
of Michigan

Application April 24, 1940, Serial No. 91,900

Term of patent 14 years

To all whom it may concern:

Be it known that I, Truman B. Funk, a citizen
of the United States, residing at Jackson, in the
county of Jackson and State of Michigan, have
invented a new, original, and ornamental Design
for a Lawn Mower Handle Crosspiece, of which
the following is a specification, reference being
had to the accompanying drawing, forming part
thereof, wherein:

Figure 1 is a side elevational view of a lawn
mower handle crosspiece showing my new design.

Fig. 2 is an enlarged perspective view looking at
an angle toward one end.

Fig. 3 is an end elevational view.

I claim:

The ornamental design for a lawn mower han-
dle crosspiece, substantially as shown.

TRUMAN B. FUNK.
